Patented Aug. 2, 1921.

Inventor:
Frank A. Thill

UNITED STATES PATENT OFFICE.

FRANK A. THILL, OF CINCINNATI, OHIO.

DESIGN FOR A BUTTON OR BADGE.

58,642.

Specification for Design.

Patented Aug. 2, 1921.

Application filed October 21, 1920. Serial No. 418,630. Term of patent 7 years.

To all whom it may concern:

Be it known that I, FRANK A. THILL, a citizen of the United States, residing at #6616 Beechmont avenue, Cincinnati, in the county of Hamilton and State of Ohio, have invented a new, original, and ornamental Design for a Button or Badge, of which the following is a specification, reference being had to the accompanying drawing, forming part thereof.

The figure is a plan view of a button or badge showing my new design.

I claim:

The ornamental design for a button or badge as shown.

FRANK A. THILL.
